Morgan Manufacturing Company, Inc., a corporation of Delaware

Application January 11, 1946, Serial No. 125,462

Term of patent 7 years

(Cl. D15—8)

To all whom it may concern:

Be it known that I, Gordon E. Obrig, a citizen of the United States, residing at Brooklyn, in the county of Kings and State of New York, have invented a new, original, and ornamental Design for a Vanity Table Bench or Similar Article, of which the following is a specification, reference being had to the accompanying drawing, forming part thereof.

The figure is a perspective view of a vanity table bench, showing my new design.

I claim:

The ornamental design for a vanity table bench or similar article, as shown.

GORDON E. OBRIG.
